CLAIM

The ornamental design for a lawn mower and charging base set, as shown and described.

DESCRIPTION

FIG. 1 is a perspective view of a charging base of a lawn mower and charging base set showing the new design; FIG. 2 is another perspective view thereof; FIG. 3 is a front elevation view thereof; FIG. 4 is a back elevation view thereof; FIG. 5 is a left-side view thereof; FIG. 6 is a right-side view thereof; FIG. 7 is a top plan view thereof; FIG. 8 is a bottom plan view thereof; FIG. 9 is a perspective view of the lawn mower of the lawn mower and charging base set; FIG. 10 is another perspective view thereof; FIG. 11 is a front elevation view thereof; FIG. 12 is a back elevation view thereof; FIG. 13 is a left-side view thereof; FIG. 14 is a right-side view thereof; FIG. 15 is a top plan view thereof; FIG. 16 is a bottom plan view thereof; FIG. 17 is a perspective view of the lawn mower and charging base set; FIG. 18 is another perspective view thereof; FIG. 19 is a front elevation view thereof; FIG. 20 is a back elevation view thereof; FIG. 21 is a left-side view thereof; FIG. 22 is a right-side view thereof; FIG. 23 is a top plan view thereof; FIG. 24 is a bottom plan view thereof; FIG. 25 is an enlarged view of the enclosed portion in FIG. 1.

FIG. 26 is an enlarged view of the enclosed portion in FIG. 2;

FIG. 27 is an enlarged view of the enclosed portion in FIG. 9; and,

FIG. 28 is an enlarged view of the enclosed portion in FIG. 10.

The broken lines depict portions of the lawn mower and charging base set that form no part of the claimed design. The dash-dot lines in FIGS. 1, 2, 9, 10, 25, 26, 27, and 28 illustrate the enlarged view indicators and form no part of the claimed design.

1 Claim, 28 Drawing Sheets
